UNITED STATES PATENT OFFICE.

GOUVERNEUR G. BROWNE, OF WINCHESTER, NEW HAMPSHIRE.

RING-ROLLING MACHINE.

Application filed June 22, 1921. Serial No. 479,472.

To all whom it may concern:

Be it known that I, GOUVERNEUR G. BROWNE, a citizen of the United States, and a resident of Winchester, in the county of Cheshire and State of New Hampshire, have invented a new and useful Improvement in Ring-Rolling Machines, of which the following is a specification.

My invention relates to machines for rolling metal rings and has for its principal objects to devise a machine that will roll rings of various sectional shapes, that will roll rings free from fins and flashings, that will form rings of the exact size and cross-sectional shape desired and that will produce rings of excellent quality.

The invention consists principally in a ring rolling machine in which one of two co-operating forming rolls is mechanically fed transversely of the other during the rolling operation; it also consists in a ring rolling machine provided with means for adjusting the angular relations of the forming rolls to each other; it also consists in a ring rolling machine whose cooperating rolls contact with each other in two planes throughout the rolling operation; and it also consists in the parts and combinations of parts herein-after described and claimed.

In the drawings, which form part of this specification and wherein like reference numerals indicate like parts wherever they occur,

Fig. 1 is a plan view of a ring rolling machine embodying my invention;

Fig. 2 is an end elevation thereof;

Fig. 3 is a sectional view on the line 3—3 of Fig. 1;

Fig. 4 is a view of forming rolls of a modified design; and

Fig. 5 is a detail view of the plate on which the swivel head that supports one of the forming rolls is mounted.

Mounted on a suitable base 1 is an electric or other motor 2 whose shaft 3 is provided with a pinion 4 at one end and a bevel or other gear 5 at the other end. The pinion 4 meshes with a gear 6 secured on a spindle 7 that is journaled in suitable bearings 8 provided therefor in a housing 9. The spindle housing 9 is mounted on a carrier or frame 10 that is slidably mounted in ways provided therefor in the frame of the machine or in a suitable guide block on said frame. In order to permit movement of the spindle

housing 9 endwise without disengaging the gear 4 and pinion 6, the pinion is wider than the gear.

Parallel with the spindle 7 and secured to the spindle housing 9 by an arm 11 is a rod 12 whose ends extend into cylinders 13 and constitute pistons or plungers therefor. These cylinders 13 or fluid chambers are suitably connected with a source of air or fluid pressure to be actuated thereby. The spindle carrier is moved backward or forward by the pressure of air or other fluid under pressure admitted into one or the other of said cylinders 13 and thus causing endwise movement of the plunger rod 12 which carries with it the spindle housing and spindle 7.

Mounted on the end of the spindle 7 or integral therewith is a mounting plate 14 to which is removably secured a forming roll 15. Preferably the mounting plate is recessed to receive the end of the forming roll 15 and said forming roll is detachably secured to the mounting plate 14 by screws 16 or the like.

Disposed on a slide-way 17 transverse to the axis of the forming roll spindle 7 is a bed plate 18 on which is mounted a swivel head 19 that is provided with suitable journal bearings 20 for a second spindle 21 on the end of which is removably mounted a forming roll 22 to cooperate with the first forming roll 15.

The bed plate 18 is provided with a downwardly projecting portion 23 having a threaded hole therethrough, through which passes a feed screw 24 that is journaled in the frame of the machine and projects therefrom at one end. The projecting end of the feed screw 24 is provided with change speed and reverse gear mechanism 25 that is driven by a gear 26 on the end of a counter-shaft 27. This counter-shaft 27 has a bevel gear 28 at its other end that meshes with the bevel gear 5 on the end of the motor shaft 3. As the feed screw 24 and the forming roll 15 are driven from the same motor, the ratio between the feed of the screw and the velocity of rotation of the roll is constant for any particular setting of the change speed gear mechanism.

In the upper surface of the bed plate 18 is an undercut annular channel 29 into which extend the beveled heads of bolts 30 or the like that pass through holes provided there-

for in the base portion of the swivel head 19. The swivel head 19 is centered on an up-standing circular projection 31 on the bed plate 18 that fits in an opening in the base portion of the swivel head. The swivel head 19 is secured in position by drawing up the bolts 30 tight against the sides of the annular channel; and by loosening said bolts 30, the swivel head 19 may be rotated on said centering projection to any desired position. The annular channel 29 is provided with enlarged openings 32, corresponding to the number of securing bolts 30 and the swivel head may be lifted off of the bed plate by 15 turning it until the heads of the bolts 30 register with the enlarged openings 32 in said channel 29.

Rotatably mounted on suitable projections 33 on the swivel head above and below the forming roll 22 respectively are suitable guide rolls 34 that are adapted to engage the work as it nears the end of the rolling operation. Preferably these projections 33 are slotted and the rolls 34 are secured there- 25 to by bolts 35 passing through these slots; and the position of the guide rolls may be changed by moving the securing bolts in said slots.

The forming rolls 15 and 22 may be of 30 any suitable size and form, depending on the size and cross-sectional shape of the ring that is to be produced. I prefer to have the rolls contact in two planes that are parallel to each other and to the line of feed of 35 the transversely movable roll. By this arrangement, the work is entirely enclosed throughout the rolling operation and the formation of fins or flashings thereon is prevented.

40 In the construction illustrated in Fig. 4, the driven roll 50 is provided with a recess 51 in which the work rests and the work is rolled between the periphery of said recess in the roll and the second forming roll 52. At the beginning of the rolling operation, the 45 overall diameter of the work, (which is in the form of an annular blank of rectangular or other convenient section) is much smaller than that of the recess in the forming roll 50 and the thickness of the work is greater than that desired for the finished ring. In the 50 rolling operation, the thickness of the work is reduced and the diameter thereof is increased until it fills the recess in the forming roll. Thus, if only the annular blank is of a quality suitable for rolling and has the weight required for the product, its initial 55 size and section are of relatively minor importance.

60 The operation of the machine is as follows:

The spindle 7 is moved forward, carrying with it the forming roll 15 and the work is placed on said forming roll. The trans- 65 versely movable roll 22 is then fed forward

to engage the work and to contact with the first roll 15. The driven forming roll 15 is rotated while the other roll 22 continues to be fed forward gradually by the above described feed mechanism. This results in a 70 gradual rolling of the work to the size and shape desired. The feeding of the roll 22 is gradual and in a fixed ratio to the rate of rotation of the first roll; and thus only a small amount of work is done at a given 75 time on the stock and thus the finished ring will be of excellent quality and free from the internal stresses that result from too rapid operation on the metal in a rolling mill. After the rolling is completed, the feed is 80 reversed and the second forming roll 22 is backed away to permit the ring to be removed.

As above described, the swivel head 19 may be turned so that the forming roll 22 85 may have any desired angular relation with the driven roll 15. Thus, in Fig. 1, I have shown the two rolls as being practically parallel, whereas in Fig. 4, one is at any angle of about forty-five degrees to the other. The 90 proper set or angle of the swivel head is such that the lines of contact of the forming rolls are parallel with each other and with the line of feed of the transversely movable roll, so that the transverse feed of one 95 roll will not cause any separation of the rolls.

My ring rolling machine is well adapted for rolling rings of any desired sectional shape. The forming rolls may be modified 100 as desired and the transversely movable roll may be placed at any desired angle with the driven roll. The fixed and regular feed of the transversely movable roll insures a ring 105 of good quality.

It is obvious that numerous changes may be made without departing from my invention and I do not wish to be limited to the precise construction shown.

What I claim is:

1. A ring rolling machine comprising a pair of rotatably mounted formers relatively movably longitudinally and transversely and means for changing the angular relation of said formers to each other. 110

2. In a ring rolling machine comprising a pair of rotatably mounted cooperating forming rolls, a support for one of said rolls movably bodily endwise, and a swivel head for supporting the other of said rolls 115 in cooperative relation to said first roll, said swivel head permitting angular adjustment of said rolls relative to each other.

3. In a ring rolling machine comprising a pair of rotatably mounted cooperating forming rolls, a support for one of said rolls movably bodily endwise, a swivel head for supporting the other of said rolls in cooperative relation to said first roll, said swivel head permitting angular adjustment of said 125 rolls.

rolls relative to each other, and means for moving said swivel head to feed said second roll transversely of said first roll.

4. A ring rolling machine, comprising a rotatably mounted forming roll, a swivel head adjacent to said forming roll, a second forming roll rotatably mounted in said swivel head to cooperate with said first forming roll, means for moving said swivel head bodily so as to feed said second forming roll 10 transversely of said first forming roll, and means for rotating said first forming roll, said feed means and said rotating means having a common source of power.

Signed at Winchester, New Hampshire, 15 this 26 day of May, 1921.

GOUVERNEUR G. BROWNE.
